COOLER FOR OIL IN JOURNAL RESERVOIRS

Sven Holm and John Vickland, Wellsville, N. Y.,
assignors to The Air Preheater Corporation,
New York, N. Y.

Application October 3, 1942, Serial No. 460,598

2 Claims. (Cl. 308—77)

The present invention relates to bearings for rotary shafts and particularly to means for cooling the lubricating oil in the reservoir of the bearing.

In carrying out the present invention the end of the rotary shaft is provided with a hollow agitator member dipping into the oil pool during rotation of the shaft and having a cooling fluid continuously circulated therethrough to withdraw heat from the oil. The invention contemplates improving the cooling effect not only stirring up the body of oil but by enlarging the area in which the oil contacts a surface cooled by the circulation of the refrigerating fluid. The invention will be best understood upon consideration of the following detailed description of an illustrative embodiment thereof when read in conjunction with the accompanying drawing in which:

Figure 1 is a longitudinal sectional view through a shaft bearing embodying the present invention;

Figure 2 is a sectional view on the line 2—2 in Fig. 1; and

Figure 3 is a sectional view of a modified cooling member.

Referring first to Figure 1, the numeral 10 designates the end portion of a shaft which rotates at a slow rate of speed in a roller bearing 12 mounted in the housing 14. The bearing is partially immersed in a pool of oil 16 contained in the lower portion of the housing 17. Attached to the end of the shaft 10 for rotation therewith is a hollow agitator 20 of generally cylindrical form to which water or other cooling fluid is continuously supplied from a pipe 21 through an inlet tube 22 and from which the water is withdrawn through a passage 23 in the hub 24 to be discharged through a pipe 25. A rotary pressure joint that forms no part of the present invention is utilized at 26. As appears in Fig. 2, the cooling agitator 20 is provided with a number of radially extending hollow lobes 30 which are maintained full of cooling liquid. These radially extending lobes not only increase the amount of surface of the agitator that is contacted by the cooling fluid but also increase the amount of cooling surface over which the oil may flow to cool it by contact. To further increase the cooling action and assure circulation within the pool of oil despite the slow speed of shaft 10, the outer ends of the lobes 30 are provided with suitable members 31 extending transversely of the lobes at their tips and projecting from their leading edges, i. e. in the direction of rotation of the agitator 20. The members 31 co-act with the lobes in such manner as to form a bucket or scoop that will

pick up a small quantity of oil from the pool at the bottom of the housing 17 and carry at least part of it upwardly with the related lobe as the cooled agitator rotates.

In a Ljungstrom rotary air preheater the shaft 10 would rotate at a slow rate of speed, say three revolutions per minute; the scoop members 31 on the lobes 30 thus may pick up small quantities of oil which, when the related lobe passes the high point in the circle of rotation, flows downwardly over the surface 32 forming the leading face of the lobe as well as along the surface portion 33 of the agitator 20 that lies between two lobes. Thus, small quantities of oil spread in a relatively thin film and flow over an amount of cool surface that is considerably greater than with a simple cylindrical or disc agitator. This is because the radial lobes 30 not only increase the amount of cooling surface but the scoops 31 carry oil in contact with a cooled surface to an elevated position from which it is caused to flow as a thin film over a continuously cooled surface of relatively large area before again falling back into the pool 16. It should be observed that with the construction provided the pool 16 of oil is not cooled merely by passing a cooling member through it but that the cooling effect is augmented by continuously removing small quantities of oil from the pool and while carrying them causing them to flow over surfaces that are cooled still further during the time the oil is separated from the bath.

In the form illustrated in Figure 3 the operation is the same as described above but the cooling effect is further increased by providing several sets of transversely spaced lobes 40, 41 and 42, the lobes of each set projecting at various radial locations from a generally cylindrical body 20 of the cooling member. At circumferentially spaced intervals about the cooling member 20 dams 43 are provided between the lobe 40 and the lobe 41 and between the latter and the lobe 42 so that oil may be carried from the pool in the space between the lobes. With this form it will be seen that by providing several sets of lobes additional surfaces at 44 constituting the lateral faces of the respective lobes function as cooling surfaces as well as the faces of the lobes that are perpendicular to the axis of rotation.

50 What we claim is:

1. In combination with a shaft, a bearing and a housing therefor containing in the lower part thereof a pool of oil for lubricating the bearing; a hollow agitator member comprising a generally cylindrical body portion provided with a plu-

rality of radially extending lobes adapted to dip into the oil pool during rotation of said shaft; means for supporting said agitator on the end of said shaft so that only a portion thereof is submerged in said oil pool; and means for circulating a cooling fluid through said agitator.

2. In combination with a shaft, a bearing and a housing therefor containing in the lower part thereof a pool of oil for lubricating the bearing; a hollow agitator member comprising a generally cylindrical body portion provided with a plurality of radially extending lobes adapted to dip into the oil pool during rotation of said shaft;

means for supporting said agitator on the end of said shaft so that only a portion thereof is submerged in said oil pool; scoop elements on the tips of said lobes extending forwardly from the leading edge thereof for carrying quantities of oil from said pool to an elevated position from which they may flow over the extended surfaces provided by said lobes and the surface of said agitator between said lobes; and means for circulating a cooling fluid through said agitator.

SVEN HOLM.
JOHN VICKLAND.
